AUTOMATIC VALVE

Theodore Kramer, Oklahoma City, Okla.

Application January 18, 1939, Serial No. 251,605

2 Claims. (Cl. 161—9)

The present invention relates to new and useful improvements in automatic valves particularly for controlling the flow of gas to burners but it will be understood, of course, that a valve constructed in accordance with the present invention may be used for any other purpose for which it may be found adapted and desirable.

The primary object of the invention is to provide, in a manner as hereinafter set forth, a valve 10 of the character described comprising a novel construction, combination and arrangement of parts through the medium of which said valve may be caused to automatically open at any predetermined time.

Another very important object of the invention is to provide, in a manner as hereinafter set forth, an automatic valve which is adapted to be opened by a conventional alarm clock.

Other objects of the invention are to provide an automatic time controlled valve which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of an embodiment of the invention.

Figure 2 is a view in side elevation thereof.

Figure 3 is a vertical sectional view, taken substantially on the line 3—3 of Fig. 1.

Figure 4 is a view in rear elevation of the device.

Figure 5 is a vertical sectional view, taken substantially on the line 5—5 of Fig. 2.

Figure 6 is a view in horizontal section, taken substantially on the line 6—6 of Fig. 4.

Figure 7 is a detail view in vertical section, taken substantially on the line 7—7 of Fig. 1.

Referring now to the drawings in detail, it will be seen that the embodiment of the invention which has been illustrated comprises a housing of suitable metal which is designated generally by the reference numeral 1. The housing 1 is provided with a front plate 2 which is removably secured in position by screws 3. The front plate 2 of the housing 1 has formed therein an opening 4 of substantially the shape shown to advantage in Fig. 1 of the drawings.

55 Removably mounted on the top 5 of the hous-

ing 1 is a conventional alarm clock 6. The reference numeral 7 designates the usual winding handle for the alarm of the clock 6. The supports 8 of the clock 6 are slidably engageable beneath retaining flanges 9 which are provided therefor on the top 5 of the housing 1.

Mounted in the housing 1 is a valve which is designated generally by the reference numeral 10. The valve 10 includes a casing 11 which is secured to the bottom 12 of the housing 1 through the medium of screws 13. The casing 11 is provided with an intake 14 and an outlet 15 which project through openings provided therefor in the side walls 16 of the housing 1. It may be well to here state that the valve 10 is interposed in the gas line to the burner.

The valve 10 further comprises a tapered plug 17 which is rotatably mounted in the casing 11, said plug having extending therethrough a port 18 for establishing communication between the intake 14 and the outlet 15. Projecting from the large end of the tapered plug 17 is a stem 19 having fixed thereon a manually operable handle 20. Formed integrally with the inner end portion of the handle 20 is an arm 21 which extends through the upper portion of the opening 4 in the front plate 2 into the housing 1 to a point adjacent the rear wall 22 of said housing. This is shown to advantage in Fig. 3 of the drawings. A nipple 23 is provided on the intake side of the valve 10 for connecting a pilot light tube thereto. A valve 24 is provided in the nipple 23 for controlling the flow of gas through the pilot tube.

Projecting from the small inner end of the plug 17 is a threaded, longitudinally grooved shank 25. Slidably mounted on the shank 25 and engaged with the inner or rear wall of the casing 11 is a washer 26. Threaded on the shank 25 is a nut 27 in the form of a ring. A coil spring 28 encircles the shank 25 and has one end engaged with the washer 26 and its other end engaged with the nut 27 for seating the plug 17 in a manner to prevent leakage.

Also slidably mounted on the shank 25 is a metallic ring 29 which constitutes means for connecting the inner end of a coil spring 30 to the plug 17 for rotating said plug to open position. The ring 29 is retained on the shank 25 through the medium of an annular nut 31 which is threaded on said shank. As shown to advantage in Fig. 5 of the drawings, the ring 29 is provided with a lug 32 on its inner surface which is engaged in the aforementioned longitudinal groove which is provided therefor in the shank 25. This groove is indicated in dotted lines in Fig. 3 of the draw-

ings. The connecting ring 29 further includes a lug 33 on its periphery which is engaged in an opening which is provided therefor in the inner end portion of the coil spring 30. The outer end 5 of the coil spring 30 is anchored to a pin 34 which is mounted on the rear wall 22 of the housing 1.

Mounted beneath the top 5 of the housing 1 is a bracket 35. Journalled at an intermediate point on the bracket 35 is a trigger 36 one end of which is engageable with the inner end portion 10 of the arm 21 for securing the valve plug 17 in closed position against the tension of the coil spring 30. A spring 37 is engaged with this end portion 15 of the trigger 36 for yieldingly urging said trigger toward operative position. Journalled in the housing 1 adjacent the other end of the trigger 36 is a lever 38. The lever 38 extends upwardly from the housing 1 adjacent the rear 20 of the clock 6, the upper end portion of said lever being in the path of the alarm winding handle 7 of said clock. A slot 39 in the top 5 of the housing 1 accommodates the lever 38. Struck from the lower end portion of the lever 38 is a lug 40 which is engageable with the adjacent end 25 portion of the trigger 36 for operatively connecting said lever to said trigger.

It is believed that the operation of the device will be readily apparent from a consideration of the foregoing. Through the medium of the handle 20, the plug 17 is rotated to closed position 30 against the tension of the coil spring 30, thus shutting off the flow of gas to the burner except through the pilot tube. The plug 17 is secured in closed position by engagement of the trigger 36 with the arm 21, as suggested in broken lines 35 in Fig. 5 of the drawings. When the alarm of the clock 6 goes off the rotating handle 1 engages and actuates the lever 38 which, in turn, actuates the trigger 36 against the tension of the spring 37 thereby releasing the arm 21 and permitting 40 the spring 30 to rotate the valve plug 17 to open position. Gas may then flow through the valve to the burner where it is ignited by the continuously burning pilot light (not shown). Of course, 45 the usual control valve on the burner has been previously set in the desired open position. The lever 38 engages one end of the slot 39 and, together with the alarm winding handle 7, is arrested thereby. It will thus be seen that a valve 50

has been provided which, through the medium of a conventional alarm clock, may be caused to open at any predetermined time.

It is believed that the many advantages of an automatic valve constructed in accordance with 5 the present invention will be readily understood and although a preferred embodiment of the device is as illustrated and described, it is to be understood that changes in the details of construction and in the combination and arrangement of parts may be resorted to which will fall within the scope of the invention as claimed. 10

What is claimed is:

1. A device of the class described comprising a housing, means for securing an alarm clock on 15 said housing, a valve mounted in the housing and including a casing adapted to be interposed in a conduit, a ported plug rotatably mounted in the casing for controlling the conduit, a shank on one end of the plug, a spring operatively connected 20 to said shank for rotating the plug to open position, an arm fixed on the other end of the plug, a trigger pivotally mounted in the housing, one end of said trigger being engageable with the arm for releasably securing the plug in closed position against the tension of the spring, and a lever pivotally mounted in the housing and extending upwardly therefrom in the path of the winding handle of the alarm of the clock for engagement and actuation thereby, said lever being 25 operatively connected to the other end portion of the trigger for actuating same for releasing the arm. 30

2. A device of the class described comprising a valve including a casing, a ported plug rotatably 35 mounted in said casing, a threaded shank on one end of the plug having a longitudinal groove therein, a ring mounted on said shank and including a lug on its inner surface engaged in the groove, another lug on the periphery of said ring, 40 a retaining nut for the ring threaded on the shank, a coil spring encircling the shank and having one end anchored to a support, the other end portion of said coil spring having an opening therein for the reception of the second named 45 lug for operatively connecting the coil spring to the plug for rotating said plug to open position, and means for releasably securing the plug in closed position. 50

THEODORE KRAMER. 50
